Edward N. Jacobi, Milwaukee, Wis., assignor to
 Briggs and Stratton Corporation, Milwaukee,
 Wis., a corporation of Delaware

Application December 19, 1928
 Serial No. 326,933

27 Claims. (Cl. 200—7)

This invention relates to certain new and useful improvements in switches and refers more particularly to a combination ignition and lighting switch for automotive vehicles and the like.

- 5 Switches of this type are usually mounted on the dash board of the vehicle or at the lower end of the steering column, and when so mounted its actuator extends upwardly through the column to be controlled at the steering wheel.
- 10 Heretofore, the combining of ignition and lighting switch instrumentalities in a single unit has necessitated a complicated construction due to the large number of combinations necessary and, therefore, this invention has as an object to
- 15 provide a switch mechanism of the character described in which the desired number of combinations are obtained without complicating the design of the switch.

Another object of this invention resides in the provision of a switch mechanism of the character described in which the ignition switch is substantially apart from the lighting switch but is actuated by the same control.

Another object of this invention resides in the provision of a switch mechanism of the character described in which the ignition switch is mounted within the usual enclosing case and in which the lighting switch proper is provided with means for holding the ignition switch open

30 during certain of its positions.

And a further object of this invention resides in the provision of a switch mechanism of the character described in which means are provided for normally yieldably urging the ignition switch to closed position and in which movement of the actuator simultaneously controls the lighting switch and moves the ignition switch to its open position when so desired.

And a still further object of this invention resides in the provision of a switch mechanism of the character described having a terminal head upon which a plurality of fixed contacts are mounted to be selectively engaged by a contactor and from which ignition switch terminals

45 extend which are adapted to be bridged by a second contactor and in which a single actuator moves both contactors to simultaneously control the ignition and lighting switches.

With the above and other objects in view

50 which will appear as the description proceeds, my invention resides in the novel construction, combination and arrangement of parts substantially as hereinafter described and more particularly defined by the appended claims, it being understood that such changes in the precise

embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a transverse, sectional view illustrating a switch mechanism embodying my invention, said view being taken on the plane of the line 1—1 of Figure 2;

Figure 2 is an end view taken on the plane of the line 2—2 of Figure 1;

Figure 3 is a cross sectional view taken through Figure 1 on the plane of the line 3—3;

Figure 4 is a view similar to Figure 3 illustrating the switch instrumentalities in another position;

Figure 5 is a perspective view of the actuating lever;

Figure 6 is a perspective view of the actuator carrying plate or disc;

Figure 7 is a perspective view of the actuator;

Figure 8 is a perspective view of the spider contactor which is selectively engageable with the fixed contacts of the terminal head, and

Figure 9 is a fragmentary, detail view taken through Figure 3 on the plane of the line 9—9.

Referring now more particularly to the accompanying drawings, in which like numerals designate like parts throughout the several views, the numeral 10 represents the enclosing case in which the switch instrumentalities are confined

90 and which in the present instance is illustrated as mounted at the back of a dashboard 11 which is apertured, as at 12, to permit the extension

therethrough of an actuating lever 13. The inner end of the lever 13 likewise extends through

95 an opening 14 in the bottom 15 of the enclosing case to be drivingly connected with the switch instrumentalities in a manner to be later described. The bottom 15 of the case is pre-

900 ferably struck inwardly, as at 16, to provide a bearing with which a laterally directed flange 17, formed on the extreme inner end of the lever 13, is engageable.

The open side of the enclosing case 10 is covered by a terminal head 18 preferably formed of a pair of discs 19 made of fiber, or other like insulating material, in juxtaposition and maintained assembled with the case by a plurality of prongs or lips 20 extended from the wall of the case and struck over the edge of the ter-

5 minal head as best illustrated in Figure 2. Two fiber discs are used to facilitate manufacture as by so doing it is possible to stamp the separate discs from sheet material, as will be readily apparent to any one skilled in the art.

10 A plurality of fixed contacts 21 are disposed in counterbored apertures formed in the terminal head and have their inner faces or heads flush with the inner surface thereof and their outer ends passed through and riveted over terminal members 22. The contacts are arranged circumferentially about the axis of the switch mechanism and are located at predetermined points, and the terminals 22 are adapted to have 15 conductors, not shown, connected therewith to lead to the different lighting fixtures of the vehicle with which the switch is used.

20 A substantially spider shaped contactor 23 having radial arms 24, the outer ends of which are cupped to form contactor fingers 25 is disposed within the enclosing case to be selectively engaged with the contacts 21. The contactor 23 is preferably stamped from relatively light metal and is held in position and strengthened by an 25 actuator 26 likewise stamped from bendable metal but of relatively heavier stock.

29 The actuator 26, roughly, conforms to the shape of the contactor 23 and has laterally struck portions 27 which are engageable with the cup shaped fingers 25 of the contactor 23 to impart movement to the contactor.

35 A mounting disc 28 preferably formed of fiber or other like insulating material is fixed to the back of the actuator 26 by means of ears or lugs 29 struck rearwardly from the actuator. Two of the ears or lugs 29 pass through openings 30 in the disc and are struck over the opposite side thereof and the third is engaged in a notch or recess 31 formed in the edge of the disc 28 and is 40 also struck over the opposite side of the disc. The disc is in turn carried by the actuating lever 13 being secured thereto in a similar manner by having ears or lugs 32 which extend from the inner end of the lever passed through openings 45 33 in the disc and struck over its inner face. Thus it will be seen that the contactor 23 through the actuator 26 and the disc 28 is movable upon actuation of the lever 13.

50 Pressure is applied to the contactor 23 to insure good electrical connection between its contactor fingers 25 and the contacts 21 by expandable springs 34 having one end engaging the inner face of the disc 28 and their other ends received within the cup shaped fingers 25.

55 The mechanism so far described constitutes the lighting switch. The ignition switch is disposed within the interior of the case 10 and is located adjacent the axis of the switch mechanism. The terminals of the ignition switch are 60 formed by lugs 35 and 36 extended into the interior of the case through the terminal head and respectively carried by an ignition terminal 37 and a battery terminal 38. The terminal member 37 is secured to the head 18 by a rivet 39 or the like having its head received in a counter-sunk aperture, not shown, in the back of the terminal head and the terminal member 38 is secured in position by a pair of ears or lugs 40 struck from its opposite sides and passed through 65 suitable apertures in the terminal head to be turned over at its inner side, as illustrated.

70 The lugs 35 and 36 are adapted to be electrically connected by a V shaped conductor 41 preferably formed of a relatively thin flexible strip of conducting material and having one end

80 at all times in engagement with the lug 36. The ends of the flexible conductor 41 have rectangular openings 42 and 42', which when the contactor is in position align with similarly shaped openings 43 in the ends of the lugs 35 and 36, to receive a member 44 formed of insulating material.

85 The member 44, by passing through the openings in the lugs 35 and 36 and in the ends of the contactor, maintains the contactor against displacement; and by means now about to be described moves one end of the contactor to electrically disconnect the lugs 35 and 36.

90 The lower end of the member 44 is freely slideable in the adjacent openings 42' and 43 in the lug 36 and notches or recesses 44' formed in opposite sides of the member, at a medial point, are adapted to receive the ends of the opening 42 in the other end of the contactor, whereby 95 movement of the member 44 moves the upper or free end of the contactor.

100 The length of the opening 42 is substantially equal to the distance between the recesses or grooves 44', and a slot 45 extending from the outer end of the opening to the end of the contactor permits the insertion of the member 44 into the opening, the relatively pliable split ends forming the sides of the slot, flexing as will be readily apparent.

105 An expansile spring 46 surrounds the member 44 and is confined between the ends of the U shaped contactor to at all times yieldably urge the free end thereof toward engagement with the lug 35 and to insure good electrical connection between its other end and the member 36, 110 and a suitable washer 47 is positioned between the free end of the contactor 41 and the adjacent end of the spring to prevent localized pressure on the flexible contactor.

115 The upper end of the member 44 is preferably rounded and is adapted to be engaged by a cam 48 formed on the actuator 26 by pressing outwardly a portion of its side, to be moved thereby 120 to disconnect the terminals of the ignition switch when the lighting switch is in certain of its positions. The major portion of the cam 48 is disposed circumferentially with respect to the axis of the mechanism so that no movement is imparted to the member 44 after the cam is in full engagement therewith but one end thereof 125 is directed outwardly, as at 49, to have its outermost end positioned outwardly of the rounded end of the member 44 when in its extended position so that the cam readily rides onto it as the actuator is rotated.

130 The position of the cam with respect to the non-rotatable member 44 and the fixed contacts, with which the contactor 23 is engageable is such that it is engaged with the member 44 whenever the switch is in its "off" position illustrated in Figure 3 and whenever it is moved to its "parking" position or that directly adjacent the "off" position and obtained by movement of the lever 13 toward the left with respect to Figure 3. During all other positions of the 140 switch, one of which is illustrated in Figure 4, the actuator is turned so that the cam 48 is free of the end of the plunger to permit the spring 46 to maintain the ignition circuit closed through the contactor 41.

145 During the depression of the member 44 by the cam 48 to electrically disconnect the switch terminals 35 and 36, the spring 46 applies a force to the actuator through the medium of the cam 48. The application of the force of the spring 150

to the actuator tends to shift the entire actuator sidewise within the casing. To offset this tendency, and to insure freedom of action during the time the ignition switch is held open 5 against the action of its spring 46, a lug 28' is formed on the fiber disc 28 directly opposite the cam 48. This lug 28' bears against the adjacent side wall of the casing and supports the actuator against the force of the spring. Being comparatively short, the engagement of the lug 28' with the casing side wall does not add any appreciable friction and does not retard free actuation of the switch.

The contact pressure springs 34 which are confined between the cup shaped fingers 25 and the flat plate 26 of the driver oppose any tendency on the part of the spring 46 to tip the actuator about the point of engagement of the lug 28' with the casing side wall.

From the foregoing description, taken in connection with the accompanying drawings, it will be readily apparent to those skilled in the art to which an invention of the character described appertains, that I provide an improved construction 20 for a combination ignition and lighting switch in which simple means are provided for maintaining the ignition circuit open upon movement of the switch to either its off or parking positions and in which the ignition circuit is closed throughout all of the other positions of the lighting switch.

What I claim as my invention is:

1. In a switch mechanism of the character described, a terminal head, fixed contacts carried by the terminal head, switch instrumentalities selectively engageable with the fixed contacts, means for moving said switch instrumentalities to different positions, a pair of switch terminals carried by said terminal head, a contact carrier member carried by both of said terminals, a contactor carried by said carrier and adapted to bridge the terminals and means to move the carrier upon movement of the switch instrumentalities whereby the contactor is moved into and out of engagement with the switch terminals.

2. In a switch mechanism of the character described, a terminal head, fixed contacts carried by the terminal head, a contactor selectively engageable with the fixed contacts, an actuator 50 for moving the contactor to different positions, a pair of switch terminals carried by the terminal head, a second contactor carried by both of said switch terminals and adapted to electrically connect the same, and means carried by the actuator for moving the second contactor to disconnect the switch terminals when the first mentioned contactor is moved to certain of its positions.

3. In a switch mechanism of the character described, a terminal head, fixed contacts carried by the terminal head, a contactor selectively engageable with the fixed contacts, an actuator for moving the contactor to different positions, a pair of switch terminals carried by the terminal head, a flexible metal strip to electrically connect the switch terminals, means normally yieldably urging the end portions of the flexible strip into engagement with both of said switch terminals, a member operable to move one end portion of the strip out of contact with its respective switch terminal, and means carried by the actuator for moving said member.

4. In a switch mechanism of the character described, a terminal head, fixed contacts carried by the terminal head, a contactor selectively

engageable with the fixed contacts, an actuator for moving the contactor to different positions, a pair of switch terminals carried by the terminal head, a flexible conductor to electrically connect the switch terminals, means normally yieldably holding the conductor in electrical engagement with both of said switch terminals, a member operable to move the conductor out of contact with one of the switch terminals, and cam means carried by the actuator for moving said member.

5. In a switch mechanism of the character described, a terminal head, fixed contacts carried by the terminal head, a contactor selectively engageable with the fixed contacts, an actuator for moving the contactor to different positions, terminal members carried by the terminal head and having a portion extended from the terminal head to provide switch contacts, a second contactor carried by said switch contacts and normally yieldably bridging the same, and means carried by the actuator for moving the second contactor to disconnect the switch contacts when the first-mentioned contactor is moved to certain of its positions.

6. In a switch device of the character described including an enclosing case, a terminal head closing the case and having fixed contacts, a contactor selectively engageable with the fixed contacts, an actuator for moving the contactor to different positions, terminal members mounted on the outside of the terminal head and having portions extended therethrough to project into the enclosing case and form switch contacts, a second contactor carried by said switch contacts and normally yieldably urged to bridge the same, and means carried by the actuator for moving the second contactor out of engagement with the switch contacts when the first-mentioned contactor is moved to certain of its positions.

7. A combination lighting and ignition switch of the character described including an enclosing case, a terminal head closing the case and having a plurality of fixed contacts mounted on the terminal head and arranged in an arc about the axis of the enclosing case, a contactor rotatably mounted for selective engagement with the fixed contacts, an actuator for imparting rotation to the contactor, a switch including a pair of spaced stationary contacts and a movable contactor, said last named contactor being carried by the stationary contacts, means constantly urging said last named contactor into engagement with both of said stationary contacts, and cam means carried by the actuator for moving the last named contactor against its urging means to open said switch when the first-mentioned contactor is moved to certain of its positions.

8. The combination with a lighting switch of the character described having an enclosing case, a terminal head closing the case, fixed contacts carried by the head, a contactor selectively engageable with the fixed contacts and an actuator for moving the contactor, of an ignition switch carried by the terminal head and comprising spaced stationary switch terminals having aligned apertures, a movable switch member adapted to bridge the switch terminals, a member slidably mounted in the aligned apertures of the terminals and connected with the movable switch member to open the ignition switch, upon being moved in one direction, spring means for yieldably urging the

- movable switch member and the member connected therewith in the opposite direction to close the ignition switch, and cam means carried by the actuator for moving said member and opening the ignition switch when the contactor is in certain of its positions.
9. In an ignition switch, a casing having a closure, a pair of spaced switch terminals fixed to said closure and having aligned apertures therein, a member of insulating material slideable in said apertures, a flexible conductor carried by said member to electrically bridge said terminals when said member is in a predetermined position, and means to move said member out of said position to electrically disconnect the conductor from one of said terminals.
10. In an ignition switch, a casing having a closure, a pair of spaced switch terminals, fixed to said closure and having aligned apertures therein, a bar passing through said apertures, a conductor carried by said bar and confined between the terminals to electrically bridge said terminals, a fixed connection between the bar and part of the conductor whereby movement of said bar in one direction disrupts the electrical connection between the terminals, and means to move said bar.
11. In an ignition switch, a casing having a closure, a pair of spaced switch terminals fixed to said closure and having aligned apertures therein, a bar of electrical insulating material passing through said apertures, means carried by said bar to electrically bridge said terminals upon movement of said bar to a predetermined position, and means to move said bar.
12. In an ignition switch, a casing having a closure, a pair of spaced switch terminals fixed to said closure having aligned apertures therein, a bar of electrical insulating material passing through said apertures, means carried by said bar to electrically bridge said terminals upon movement of said bar to a predetermined position, a spring constantly urging said means into contact with one of said terminals and means to move said bar to and from said position.
13. In an ignition switch, a casing having a closure member, a pair of spaced switch terminals fixed to said closure and having aligned apertures therein, a bar of electrical insulating material passing through said apertures, a metallic strip slidably mounted on said bar at one end thereof and fixed to said bar at the opposite end, means constantly urging said strip into contact with one of said terminals, means to move the other end of said metallic strip into contact with said other terminal.
14. In a switch mechanism of the character described including a terminal head, fixed contacts carried by said terminal head, switch instrumentalities selectively engageable with the fixed contacts, means for moving said switch instrumentalities to different positions, switch terminals carried by the terminal head having aligned apertures therein, a bar of insulating material mounted for movement in said aligned apertures, a contactor mounted on said bar and adapted to bridge said terminals in one position thereof, means whereby the contactor is moved to connect said terminals when the switch instrumentalities are moved to certain of their positions.
15. In a switch mechanism of the character described, an enclosing casing, a pair of spaced switch contacts carried by one wall of the casing and disposed within the casing, a bridging contactor adapted to electrically bridge said switch contacts, a member connected with the bridging contactor and operable upon movement in one direction to disconnect the contactor from one of the contacts, a spring to oppose such movement of said member, an actuator having a part disposed within the casing engageable upon movement to a predetermined position with said member to move the same against the action of said spring, and means connected with said actuator and engageable with one inner wall of the casing to support said part of the actuator against the reaction force of the spring.
16. In a switch mechanism of the character described, a casing, a terminal head closing the casing, stationary contacts carried by the terminal head, rotatable switch instrumentalities within the casing selectively engageable with the stationary contacts, an actuator for said switch instrumentalities, a pair of spaced switch contacts carried by the terminal head and disposed within the casing, a bridging contactor to electrically bridge said switch contacts, a member connected with said bridging contactor and operable upon movement in one direction to disconnect the bridging contactor from one of said contacts, a spring to oppose such movement of said member, a cam part carried by the actuator engageable with said member when the actuator and the switch instrumentalities are in certain positions to move said member against the action of said spring, and means carried by the actuator and engageable with an inner wall of the casing to provide a support for the actuator against the reaction force of said spring.
17. In a switch mechanism of the character described, an enclosing casing, a switch device within the enclosing casing comprising a movable contactor normally in a closed position, a spring to yieldably hold said contactor in its normally closed position, an actuator movable within the casing and having a part operable against the action of said spring to move the contactor to its open position, and means connected with the actuator and engageable with an inner wall of the casing to support the actuator against the reaction force of the spring.
18. In a switch mechanism of the character described, an enclosing casing, rotatable switch instrumentalities within the casing, actuating means for the rotatable switch instrumentalities including an insulating member and a handle connected with the insulating member, an auxiliary switch device within the casing including a movable contactor normally in closed position, a spring to yieldably hold the contactor in closed position, a member operable against the action of the spring to move the contactor out of closed position, and cam means carried by the insulating member and operable upon movement of said member by the handle to a predetermined position to move the contactor actuating member against the action of said spring.
19. In a switch mechanism of the character described, an enclosing casing, rotatable switch instrumentalities within the casing, actuating means for the rotatable switch instrumentalities including an insulating member and a handle connected with the insulating member, an auxiliary switch device within the casing including a movable contactor normally in closed position, a spring to yieldably hold the contactor in closed position, a member operable against the action of the spring to move the contactor out of closed position, and cam means carried by the insulating member and operable upon movement of said member by the handle to a predetermined position to move the contactor actuating member against the action of said spring.

- action of the spring to move the contactor out of closed position, and cam means carried by the insulating member and operable upon movement of said member by the handle to a predetermined position to move the contactor actuating member against the action of said spring, and said insulated member being engageable with an inner wall of the casing to be supported thereby against the reaction force of the spring. 5
20. In a switch mechanism of the character described, an enclosing casing, rotatable switch instrumentalities within the casing, actuating means for said switch instrumentalities comprising, an insulated plate rotatable within the 10 casing, means to turn said plate from without the casing, a driver carried by the plate and engaging the switch instrumentalities, an auxiliary switch device within the casing including spaced stationary contacts and a movable contactor normally electrically bridging said stationary contacts, a member operable to move the contactor out of its bridging position, and a cam on the driver operable to actuate said last named member upon movement of the driver with the 15 actuating means to a predetermined position. 15
21. In a switch mechanism of the character described, an enclosing casing, rotatable switch instrumentalities within the casing, actuating means for said switch instrumentalities comprising, an insulated plate rotatable within the casing, means to turn said plate from without the casing, a driver carried by the plate and engaging the switch instrumentalities, an auxiliary switch device within the casing including spaced 20 stationary contacts, and a movable contactor normally electrically bridging said stationary contacts, a member operable to move the contactor out of its bridging position, a cam on the driver operable to actuate said last named member 25 upon movement of the driver with the actuating means to a predetermined position, a spring to oppose movement of said member to move the contactor out of its bridging position, said spring tending to shift the insulated plate and driver 30 out of their normal positions upon engagement of the cam means with said member, and means whereby the reaction force of the spring imparted to the driver and insulated plate is taken up by the casing directly to hold said driver 35 and plate against shifting. 40
22. In a switch device of the character described, a casing, rotatable switch instrumentalities within the casing, actuating means for the switch instrumentalities including a rotatable driving element, means to turn said driving element from without the casing, an auxiliary switch device within the casing including a movable contactor normally in closed position, a spring to yieldably maintain said contactor in 45 closed position, a member connected with the contactor and operable upon movement in one direction to move the contactor against the action of the spring, a part carried by the rotatable driving element and engageable with said last named member to move the same against the 50 action of said spring, whereby the reaction force of the spring is applied to the driving element, means on said driving element engageable with an inner wall of the casing to support the driving element against movement by the reaction force of said spring, said reaction force tending to tilt the driving element about its engagement with the casing, and contact pressure springs between the switch instrumentalities and the rotatable 55 driving element to afford contact pressure for 60
- the switch instrumentalities and to counteract the tendency of the first named spring to tilt the driving element. 65
23. In a switch mechanism including a plurality of stationary contacts, a movable contactor having a plurality of spaced contacts movable into selective engagement with the fixed contacts, and a driver to actuate said movable contactor, said driver having a substantially flat wall coextensive with the contactor and having outstruck flanges extending from the wall to embrace the spaced contacts directly adjacent their engagement with the fixed contacts. 70
24. In a switch device of the character described, a terminal head, fixed contacts carried by the terminal head, a plurality of connected movable contacts selectively engageable with the fixed contacts, and means to actuate said movable contacts comprising an all metal driver having means formed integral therewith to substantially embrace the spaced movable contacts adjacent the terminal head. 75
25. In a switch mechanism of the character described, a terminal head, fixed contacts carried by the terminal head, a movable contactor having a plurality of spaced substantially cup-shaped contact points selectively engageable with the fixed contacts, a driver for said movable contactor comprising a plate and means on the 80 plate engaging said substantially cup-shaped contact points near the terminal head to apply the driving force of the driver to the movable contactor closely adjacent the terminal head, and contact pressure springs received in the 85 substantially cup-shaped contact points and confined between the bottoms of said cup-shaped contact points and the plate. 90
26. In a switch mechanism of the character described, an enclosing casing, a terminal head 95 providing a closure for the casing, stationary contacts on the terminal head, a movable contactor within the casing selectively engageable with the stationary contacts, and means to actuate said movable contactor comprising a plate 100 of insulating material, a metal driver attached to said plate and having a plurality of laterally directed flanges substantially embracing spaced portions of the contactor to impart sidewise movement to the contactor upon actuation of 105 the plate, contact pressure springs confined between the contactor and said driver, and a handle projecting through an opening in one wall of the casing and attached to the plate. 110
27. A switch mechanism of the character described comprising, a substantially cup-shaped enclosing casing having an opening in its bottom wall, a terminal head closing the open front of the casing, stationary contacts on the terminal head, a movable contactor within the casing selectively engageable with the stationary contacts, actuating means for the contactor comprising, a disc of insulating material receiving support from the apertured bottom wall of the 115 casing, an all metal driver attached to the insulated disc and having flanges projecting therefrom to substantially embrace spaced portions of the contactor and transmit sidewise motion of the disc to the contactor adjacent the terminal head, contact pressure springs confined 120 between portions of the contactor and the driver, and a handle projecting into the casing through the aperture in its bottom wall and attached to the insulated disc. 125
